W. J. CAMERON

ILLUMINATED TONGUE DEPRESSOR

Filed Oct. 27, 1922

UNITED STATES PATENT OFFICE.

WILL J. CAMERON, OF CHICAGO, ILLINOIS.

ILLUMINATED TONGUE DEPRESSOR.

Application filed October 27, 1922. Serial No. 597,401.

To all whom it may concern:

Be it known that I, WILL J. CAMERON, a citizen of the Dominion of Canada, residing at Chicago, in the county of Cook and State 5 of Illinois, have invented a new and useful Improvement in Illuminated Tongue Depression, of which the following is a specification.

My invention relates to tongue depressors, 10 and has particular reference to a structure of this character that is capable of being illuminated and collapsible so that it may be folded to be conveniently stored or carried in the pocket.

15 Among the objects of my invention are the provision of a tongue depressor having a blade holder or carrier that is hingedly connected to the handle, and the latter is provided with suitable means for illumination so that when the device is in use the cavity of the mouth and the palatal and lower portions of the throat will be illuminated and may be readily examined. Another object is to provide a structure in 20 which the usual wooden blades or spatula are readily insertable in the hinged carrying member and may be quickly removed therefrom, or a metal spatula can be substituted for a wooden blade when it is necessary for 25 the physician or surgeon to perform an operation. Another object is to provide illuminating means upon a holder or handle; the parts of the structure being so arranged that the liability of short circuiting the current, or of shocking the patient is entirely 30 eliminated. Also, in this latter connection, I have constructed the appliance so that the conductor wires leading from the lamp socket are embedded firmly in insulating 35 material and lead to the end of the handle opposite the light so that the lead wires with which the handle or holder is connected will be out of the way and not interfere with the surgeon or physician. A still further 40 object resides in the provision of a hinged structure for removably connecting the blade holder or carrier to the handle so that the parts may be readily separated for the 45 purpose of sterilization. A further object 50 of my invention is to provide a structure that may be folded in a compact manner so that it will occupy a relatively small space for storage, or may be conveniently carried in the pocket of the operator. All of the 55 foregoing, and divers other objects, I prefer to accomplish by means of the structure

hereinafter described, and which is more particularly pointed out in the claims. Reference will now be had to the accompanying drawings that form a part of this specification and which show a typical or preferred embodiment of my invention. 60

In the drawings:

Fig. 1 is a vertical side elevation of the tongue depressor and handle portion, the 65 latter being partly broken away to disclose its interior.

Fig. 2 is a central vertical section of the structure illustrated in Fig. 1, the same being fragmental and enlarged. 70

Fig. 3 is a vertical transverse section on line 3—3, Fig. 1, looking in the direction of the arrows.

Fig. 4 is a transverse horizontal section taken on line 4—4, Fig. 2, looking in the 75 direction of the arrows.

Fig. 5 is a perspective of a metal tongue depressor which is interchangeable with the well known wooden spatula.

Similar reference characters have been 80 employed to designate the same parts throughout the several views, and, by reference to Fig. 1, it will be observed the structure preferably comprises a handle member 6, which, as seen in Figs. 1 and 4 85 of the drawings, is hollow and is substantially oval or elliptical shape in cross-section. The handle member is preferably formed of insulating material, such as the well known bakelite, gutta percha, or similar 90 material, to insure insulation, and at its lower end is reduced in diameter, and terminates in an extension 7 of cylindrical or circular cross-section to which is attached a ferrule or sleeve 8 of the electrical plug connection type. A terminal 9 is provided in the end of the cylindrical extension 7 to which a conductor wire 10 is suitably connected, and the opposite conductor wire 11 is connected to ferrule or sleeve 8. In order 95 to insure the separation and insulation of these conductor wires 10 and 11, they are embedded in opposite portions of the wall of the handle, preferably diametrically opposite each other, as shown in Figs. 1, 2 and 100 4, which prevents the rupture of the wires and also avoids short circuit in the current and guards shocking the patient.

At the upper end of the handle the same is provided with an oblique lateral extension 110 12 that is hollow and has embedded in it the threaded metallic shell 13 of the well-known

electrical socket connection, to which the adjacent end of conductor wire 11 is suitably connected, preferably by solder or otherwise. A terminal 14 is embedded centrally in the inner end of the hollow portion of extension 12 and spaced and insulated from socket 13 into which it projects, and conductor wire 10 is connected to this terminal 14 so that when a lamp or bulb 15 is screwed into socket 13 into which it projects, and conductor wire 10 is connected to this terminal 14 so that when a lamp or bulb 15 is screwed into socket 13 into contact with terminal 14 the circuit will be formed through the lamp filament. The outer end of extension 12 is provided with an enlarged portion 16 that has provided upon opposite sides, preferably horizontally aligning recesses 17 so that enlargement 16 is thereby bifurcated which permits of the ready manipulation of a miniature bulb 15 when being screwed into the socket. It will also be noted that upon opposite sides of the recess is provided a shield or guard that shades the light from the operator's eyes and also protects the bulb against accidental breakage in the event the patient should suddenly close his teeth against the same.

The holder or carrier for the spatula or tongue blade comprises a metal plate 18 that is provided adjacent its hinged end with a longitudinal embossment 19 that provides a reinforcing rib, and said plate terminates adjacent the same in lobes or ears 20 that provide means for hinging the same upon the handle member, as will shortly be described. The longitudinal side edges of plate 18 are bent downwardly to provide side-walls 21 and then horizontally parallel and below top wall 19 to provide spaced bottom walls 22 that are somewhat yielding. This provides a box-like structure that will readily yield and frictionally hold the wooden spatula 23 when inserted therein, as seen in Figs. 1 and 3 of the drawings. This also permits the wooden spatula to be inserted whenever the physician or surgeon is examining a patient's mouth or throat, and the spatula may be readily removed and discarded after each examination. In the event an operation is to be performed it is customary to provide a more rigid structure than the wooden spatula, in which event a metal blade is employed, similar to that shown in Fig. 5, in order to give the structure greater strength. As it is necessary, in performing operations to use considerably more force against the muscles of the tongue and throat, owing to the fact that the patient is usually under anesthetic, this metal blade 24 has its outer end curled downwardly, as at 25, and is provided with a central elongated opening 26 that extends longitudinally thereof.

65 The handle 6 adjacent its upper or outer

end and contiguous to the extension or oblique member 12 is provided with a rounded embossment 27 that is bored horizontally, or axially thereof, to receive shank 28 of a headed bolt 29. The ears or lobes 20 of the holder structure are apertured, and these apertures are placed in registry with the bore of embossment 27 after which bolt 28 is passed through the same and mounted into place by means of a nut 30. 75

For convenience in handling the structure, I have provided a ring 31 that is snapped into opposite recesses 32 upon sides of the head of bolt 29 and which may be folded down flatwise when not in use. When the structure is being used, the holder for the spatula or tongue blade is raised upwardly so that embossment 19 contacts the under surface of enlargement 16 of extension 12, and a downward pressure of the handle in this position with the spatula or blade against the tongue will hold the structure in position. When not in use holder 18 may be folded flat against the handle member, as seen in dotted lines in Fig. 1 of the drawings.

In using the metal spatula or blade, shown in Fig. 5, the carrier is preferably removed and the perforated hinge lugs 33 are placed upon opposite ends of cylindrical embossment 27 so that the metal spatula is mounted in the same manner as the holder. If desired, the metal spatula may be straight at its ends; the hinge lugs being omitted so that it is of substantially the same dimensions as the wooden spatula, and, in this event, the carrier or holder 18 need not be removed from the handle, but the metal blade may be inserted between the four walls of the carrier in the same manner as the wooden blade structure. It is obvious that other types of instruments may be employed upon the structure and the illumination from the lamp will provide ready means for examination and operation.

What I claim is:

1. An illuminated tongue depressor comprising a handle, a spatula receiving member hingedly connected adjacent one end thereto, a lateral member beyond the point of connection of said member to said handle and against which the spatula-receiving member impinges when in operation, an electric light socket in said lateral member, an electric plug connection at the opposite end of said handle, and conductors leading from said socket to said plug and embedded in the walls of the handle. 115 120

2. An illuminated tongue depressor comprising a handle, a spatula receiving member hingedly mounted at one end thereof, and a protected lamp socket above said member consisting of a lateral hollow embossment on said handle in which a metallic sleeve is secured; said embossment extended 125

beyond the outer end of said sleeve and having oppositely disposed recesses whereby to permit access to a lamp inserted therein and for the manipulation of the latter.

- 5 3. An illuminated tongue depressor comprising a handle of insulating material, a lamp socket and terminals at one end thereof, a plug and terminals at the opposite end, spaced conductors connecting the respective terminals and wholly embedded and insulated in said handle, a holder hingedly mounted on said handle adjacent said socket, and a spatula removably mounted in said holder.
- 10 10. An illuminated tongue depressor comprising a handle of insulating material, a

lamp socket and terminals at one end thereof, a plug and terminals at the opposite end, spaced conductors connecting the respective terminals and wholly embedded and insulated in said handle, a holder hingedly mounted on said handle adjacent said socket; said holder consisting of a plate provided at the portion opposite the hinge with folded over spring members whereby 25 to provide a yieldable pocket, and a spatula removably inserted in said pocket.

Signed at Chicago, county of Cook and State of Illinois, this 30th day of August, 1922.

WILL J. CAMERON.
